MANUFACTURE OF CONCRETE PILING
Birdie L. Myers, 1612 22nd St., Galveston, Tex.
Filed Apr. 13, 1962, Ser. No. 187,275
1 Claim. (Cl. 61—53.64)

This invention relates to the manufacture of concrete piling. More specifically it relates to a unique method for producing concrete in place. Even more particularly the method has to do with the drilling of holes in the ground and the installation of concrete piling poured in place.

In construction work where concrete piling is required or desirable, it is conventional practice to drill a hole in the ground to the proper depth with an earth auger and to then withdraw the auger whereupon the pile is formed by pouring concrete into the hole. Where the ground is soft and susceptible to cave-ins, it is common to insert a thin-walled metal sleeve into the hole to eliminate cave-ins before and during the pouring of the concrete. In instances where the ground is swampy or very sandy and this method is not satisfactory, it is necessary to force a thick walled steel vessel closed at the bottom into the ground and then pour it full of concrete. Since concrete piles are used in many different ground formations, many difficulties have been encountered in pouring piles in the first above mentioned manner. This invention is directed toward and does solve the many undesirable aspects of the above-mentioned methods which cause the forming of in-place concrete piles to be expensive, slow and unsatisfactory.

Various means have been devised for stabilizing soil to prevent cave-ins when the auger is withdrawn. Treatment of the soil with stabilizing chemicals has been suggested. However, these are effective only in certain soil conditions and are expensive and time consuming. Furthermore, the important problem of concrete set-up is aggravated whenever time is lost, and in any method for that matter, since it is generally impossible to mix the concrete on the job-site.

Another problem encountered in the production of in-place concrete piling is segregation of the concrete as it is poured into the hole. From any height above about three feet, concrete will segregate unless the consistency is thick, and the proper strength is unattainable in that case as well as reducing the limited time before set-up. In most cases it is almost impossible anyway to keep the proper mixture from setting-up before being poured into the hole and various retardants used always interfere with the strength.

It is, therefore, the object of this invention to manufacture concrete piling in-place. It is a further object to manufacture concrete piling in-place so as to avoid hole cave-ins. It is also an object to manufacture concrete piling in-place wherein the concrete does not segregate when poured and yet maintains maximum strength. It is finally another object of this invention to manufacture in-place concrete piling which does not set up prematurely before or during the pouring and yet maintains maximum strength. These and other objects of the invention will be apparent to those skilled in the art by the following description.

According to this invention, concrete pilings are manufactured in-place by the combination of steps which consist of drilling a hole in the ground with a tubular auger open at its lower end and provided with a bit having replaceable angled teeth and an opening in the bit for the passing of fluid, forcing the excavated material upward out of the hole with the special flights of the auger, injecting retarded concrete through the tubular auger into the hole after the bit has drilled to the desired depth, and then simultaneously withdrawing the bit and

the auger as the said concrete is pumped into the hole thus filling the hole with non-segregated concrete of the proper strength and consistency which will not set-up because of a unique retardant mixed therein.

5 In practicing this method, the earth auger is not removed when the drilling is completed and thus the auger forms at all times the wall reinforcing means for that portion of the hole not yet filled with concrete. The concept of slowly withdrawing the auger as the concrete is poured eliminates the need for extra equipment and also reduces the number of steps to be performed in forcing concrete piles into the ground and, therefore, represents a substantial saving in labor, time, and materials while still providing additional strength and efficiency to the finished pile.

The accompanying drawings will illustrate the process but are not to be construed as limiting it.

FIGURE 1 is a view of the drilling apparatus and equipment used to operate the drilling apparatus.

20 FIGURE 2 is a view of the auger and bit used to drill the earth holes.

FIGURE 3 is a view of the unique bit designed to be used in the practice of this method of drilling holes for concrete piling.

25 In FIGURE 1, the equipment may include a drilling frame 1 which is attached to and supported by the bed of a truck, tractor or other mobile equipment 2. The tubular auger 3 is shown inside the drilling frame 1 and is complete with flights and attached to the head gear 5 which serves to force the auger into the ground by its weight and also contains the hydraulic drive mechanism to turn the auger. The hydraulic fluid pump to the drive mechanism is located on the bed of the mobile vehicle 2. The head gear is raised by a cable apparatus 9 which is attached to and operated by a drive on the vehicle 2. The bit 4 is shown after a hole 10 has been drilled and just prior to the concrete being pumped through the auger and bit into the hole. After removing the auger and bit as the hole is filled with concrete 40 11, the completed concrete piling is shown as 20. The concrete is pumped by means of an air driven pump 7, through hose 6, into the auger 3 and thence into the hole. The vibrator chain 8 acts to densify the concrete as it passes through the auger and eliminates any entrained air pumped with the concrete. In addition to filling all voids in the flowing concrete by its vibrating action, vibrator chain 8 also acts to keep the concrete from separating into solid and liquid phases as it flows the length of the auger. This is accomplished by fastening the chain to head gear 5 and allowing it to hang free the length of the auger. The vibrator chain turns and vibrates with the turning action of the head gear and thereby acts to fill concrete voids and maintain the concrete in a non-segregated condition.

55 FIGURE 2 simply shows in more detail the construction of the tubular auger 12 and the flights 13. The bit 14 is attached to the bottom of the auger so that the flights of the bit line-up with the flights of the auger. The bit is constructed so that the bit teeth 15 are set in two rows each at approximately 45° with the other so that the drilling is performed in a manner which will push the earth outward and then flow evenly upward to the auger flights.

In FIGURE 3 the bit 16 is shown in even more detail 65 with the bit spirals 17 indicated. The angle of the two rows of teeth 18 can be seen and the hole 19 from whence the concrete flows can be easily identified.

When it is desired to manufacture in-place concrete piling in accordance with this method and with this apparatus, the mobile vehicle is merely moved to the desired location and the drilling frame erected in the proper manner. The auger is then rotated by the hydraulic

drive mechanism and the hole is drilled by the bit to the proper depth. Normally the approximately 30 foot auger is satisfactory for most holes but in swampy and sandy areas and where large industrial towers or heavy vibrating equipment are to be installed, holes up to 100 feet may be required. In that case, 2 or 3 or possibly 4 sections of the tubular auger will be required. This is handled in the same manner as oil field drilling wherein the head gear is disconnected from the auger and raised to the top of the frame. Another section of tubular auger is swung into place, attached and the drilling continues. When the hole is drilled to the proper depth, the rotation is stopped and the air operated concrete pump is started. All during this period and while the hole is filled with concrete, the auger acts as a wall support for the hole to prevent cave-ins and under all but extreme conditions is adequate. The concrete is then pumped in and the auger and bit are withdrawn from the hole as it fills but at a rate so that the concrete does not fall any further than about one foot and preferably the tip of the bit is in the concrete at all times.

The size of the holes which may be drilled and concrete pilings installed therein by this method vary from about six inches in diameter to as high as thirty six inches in diameter although preferably the most practical and most economic size is from about 8 inches to about 14 inches in diameter.

Perhaps the most important factor in this method of manufacturing in-place concrete piling is the composition of the concrete. The particular advantage of concrete piling is the superior strength and non-corrosive surface it possesses over conventional materials such as wood and steel. However, under differing conditions concrete loses its strength and does not properly perform its intended task. Some of these conditions are segregating, excessive or insufficient water, and premature hardening.

Segregating is when most of the aggregate falls to the bottom of the hole and the top portion consequently has inferior strength. This can be caused by allowing the concrete to free-fall too far or by using too much water. The use of excessive or insufficient water creates separate problems all in themselves. Excessive water causes segregation as noted above and results in low strength. Too much water may be used, when pumping conditions are severe or when premature hardening is imminent. Insufficient water is a common mistake in poured concrete since this eliminates segregation but it results in low strength concrete and premature hardening. The separate problem of premature set-up is the most severe in the manufacture of in-place concrete piling. When a concrete truck must travel long distances to an industrial job site, premature hardening nearly always occurs to some extent. It again is aggravated because the concrete must then be pumped through a pump, hose and tubular auger.

All of the above mentioned problems can be eliminated by using a unique retarding densifier. Besides retarding the hardening of concrete it acts as a densifier to form a stronger concrete. The specific material used in this method is a compound known to the trade as Symentard, a chemical compound manufactured by the A. C. Horn Company. This compound is constituted of minor proportions, that is, less than 5% by weight each of nitrogen, sulfur, lignin, sulfonic acid, and major proportions that is, at least 10% by weight each with the total being greater than 60% by weight of carbon, glucose, hydrogen and silica. The resulting concrete is

stronger than ordinary concrete of the same proportions of cement, sand and water and is, therefore, a necessary part of the superior concrete piling manufactured by this method.

The following example is illustrative of the concrete composition of this invention but should not be construed as limiting it in any manner.

Example I

Three concrete cylinders six inches in diameter and twelve inches long were cured, capped and broken in accordance with standard American Standard Testing of Materials Methods and Specifications. Two beams four inches by four inches by eighteen inches were cured and broken in accordance with standard ASTM specifications. All of these cylinders and beams were constructed of concrete of the following composition:

	Lbs.
Trinity Portland cement	1,128
No. 16 Colorado sand	2,630
Symentard	12
Water	520

The results showed that 28 day strength on the cylinders gave average break load of 102,000 lbs. and 7 day strength gave a break load of 45,000 lbs. The rupture modulus on the beams averaged 700. It is apparent that these results show approximately 10% greater strength than the best concrete used in bridge construction.

What is claimed is:

30 In a method for manufacturing concrete piling in-place by drilling a hole in the ground with a tubular auger having flights to remove the earth and thereafter filling the hole with concrete passing through said tubular auger as said auger is removed from said hole, the improvement which consists of drilling said hole with a tubular auger having a bit on its lower end with at least two rows of multiple teeth set at about a 45° angle with the vertical to drill a hole at least as large as the diameter of said auger, said bit having an opening into said tubular auger and flights to direct drilled material away from said opening and onto flights on said auger, and thereafter forming said concrete piling in place by air pumping through said auger into said hole concrete containing therein from 0.1% to 1.0% by weight of the concrete of a retarding densifier containing major proportions of carbon, hydrogen, glucose and silica and minor proportions of nitrogen, sulfur, lignin and sulfonic acid, said pumping of said concrete through said auger being carried out by pouring said concrete over a rotating and vibrating chain suspended inside the entire length of said auger, said vibrations being caused by the withdrawal of said auger from said hole.
